UNITED STATES PATENT OFFICE.

FRANK L. O. WADSWORTH, OF SEWICKLEY, PENNSYLVANIA

WATER-HEATER.

1,175,092.

Specification of Letters Patent.

Patented Mar. 14, 1916.

Application filed May 25, 1912. Serial No. 699,816.

To all whom it may concern:

Be it known that I, FRANK L. O. WADSWORTH, a citizen of the United States, residing at Sewickley, county of Allegheny, and State of Pennsylvania, have invented certain new and useful Improvements in Water-Heaters, of which the following is a specification.

My invention relates to control mechanism for hot water heaters on either the so-called instantaneous or the storage tank type. Some of the objects of my invention are:—first, to provide a thermostatic control mechanism which will hold the gas valve that regulates the supply of fuel to the main burners of the heater either in the full open or the completely closed position, so as to avoid the gradual turning on or shutting off of the fuel supply when the temperature of the water in the heater is near the point at which the thermostatic mechanism is desired to act; second to provide a mechanism in which the first named object is accomplished not by any direct action of the thermostatic elements on the main gas valve, but by the indirect control of pressure means which do act directly on the gas valve parts and thereby effect the movement of those parts both with rapidity and with great positiveness; third, to provide a construction of extreme simplicity that can be manufactured at small cost and one which will not be liable to get out of order under the most severe and trying service; fourth, to provide improvements whereby in instantaneous heaters, the main gas valve will be held closed, no matter what may be the position of the thermostatic control parts, when no water is flowing through the heater; and fifth, to provide a form of control mechanism which, as above indicated, may be, if desired, used interchangeably on either type of heater, subject only to such mechanical modification as may be made by anyone skilled in the art of water heater construction. Other objects of my invention will appear more fully after the various structures, which I have illustrated as different embodiments of my invention have been described.

In the drawings which form a part of this specification, Fig. 1 illustrates in side elevation the general construction and arrangement of parts of a storage tank heater

to which one of my improved control mechanisms is applied; Fig. 2 is an enlarged vertical cross-section through the center of the control mechanism shown in Fig. 1; Fig. 3 is a rear elevation of one of the parts shown in Fig. 2; Fig. 4 is an enlarged cross-sectional view through a second form of control mechanism which also embodies my improvements, and may be used in place of the mechanism shown in Figs. 1, 2 and 3; Fig. 5 is a detail view of a part of the construction illustrated in Fig. 4; Fig. 6 is a view, similar to those of Figs. 2 and 4, showing other embodiments of my invention; Fig. 7 is a vertical cross-section of one of my improved control mechanisms particularly designed for use with a heater of the so-called instantaneous type, this mechanism including means for holding the main gas valve closed when no water is flowing through the heating receptacle; Fig. 8 illustrates a modification of part of the construction shown in Fig. 7; Fig. 9 illustrates another embodiment of my invention as applied to the control mechanism of an instantaneous coil heater; and Figs. 10 and 11 are detail views (full size) of a thermostat construction which may be used in conjunction with the mechanisms of the preceding figures.

Referring first to the general arrangement of parts illustrated in Fig. 1, A is a storage tank or reservoir having a cold water inlet pipe B leading from the main and a hot water outlet pipe C leading to the house fixtures; D is the casing of the heater, which heater may be of any approved type; E are the heater coils leading at their upper ends into a header F and at their lower ends into a header G; H is the gas inlet pipe; I is the gas pipe leading from the control mechanism to the burner of the heater; K are the gas burners which are located beneath the coils of the heater and may be of any preferred type; L is the thermostatic controlling mechanism for governing the supply of gas to the burners; M is a casing which contains the controlling mechanism for governing the operation of the gas valve which is also contained in the casing; N is the hot water riser leading from the header F to the reservoir A; and O is the return pipe leading from the reservoir to the lower header G.

Referring now to Fig. 2 in connection with Fig. 1; 1 indicates the head of the storage tank A, to which the casing M containing the control mechanism is attached in any suitable manner as by providing said casing with a spud 2 which screws into a plate 3 riveted to said wall. Gas is let into this casing through the supply pipe H which communicates with the right hand end of the casing chamber, and the main gas valve 4 which controls the passage of fuel to the gas outlet pipe I is mounted on a thin leather diaphragm 5 which is clamped in position against the front head of the casing M by means of a shell recessed cap 6. The space between the diaphragm 5 and cap 6 is provided with two port openings 7 and 8 which may be closed respectively by the puppet valves 9 and 10 that are held against the leather faced seats 11 and 12 by means of springs 13 and 14. The first valve 9 is provided with a stem 15 which passes loosely through a lug projecting inwardly on the wall of the gas valve casing M and is threaded at the right hand end to receive an adjustable thumb nut 16 access to which can be obtained by removing the cap 17. The lower valve 10 is placed in a tubular recess 18 which is closed at the right hand end by a stuffing box cap 19 through which the stem 20 of the valve passes, and the outer end of this stem is threaded to receive a second adjustable thumb nut 21, this thumb nut being also accessible by the removal of a cap 22. The central spud 2 of the gas valve casing is perforated and threaded to receive and support the thermostat member which projects horizontally into the water in the tank A. This thermostat is of the usual composite construction comprising an outer expansible tubular element 23 of brass, copper, or other metal having a high coefficient of expansion and an inner negative element 24 of iron, invar metal, porcelain, carbon or other material having a very low coefficient of expansion, the inner end of the negative element being abutted against or secured to and closing the inner end of the outer element, and the outer end of said negative element terminating in a pivot point which engages with a coned recess in an adjustable plug 25 at the center of the thermostat lever 26. This thermostat lever is provided with a V-shaped slot 27 (see Fig. 3) which is filed or machined across the back of the lever prior to the insertion of the plug 25, and serves to receive the pivot points of the supporting screws 28 on which the lever is mounted, these screws being located symmetrically on each side of the central plug 25, one behind and the other in front of the sectional plane of Fig. 2. The two opposite ends of the thermostat lever 26 are conically perforated to allow the passage of the

valve stems 15 and 20, and a compression spring 29 is provided to keep the lever 26 in operative engagement with the terminal pivot point of the negative thermostat element 24. The main gas valve 4 is threaded at its center to receive an adjustable screw 30, the end of which is connected to a weak tension spring 31 that normally holds the gas valve lightly against its seat. By turning the screw 30 the tension of the spring 31 can be varied, access to this screw being obtained by removing the cap 32.

The operation of this device is as follows: When the temperature of the water in the tank A is at or above the point at which it is to be maintained the thermostat is expanded sufficiently to allow the spring 29 to bring the upper arm of the thermostat lever 26 into engagement with the thumb nut 16 and thereby lift the valve 9 from its seat admitting gas to the shallow chamber between the diaphragm 5 and the cap 6. The pressure of this gas on the back of the diaphragm 5, supplemented by the slight pull of the tension spring 31, keeps the gas valve 4 against its seat and prevents all fuel flowing from the supply pipe H to the outlet pipe I leading to the main burners. As the temperature of the water in the tank falls the thermostat member contracts and moves the upper end of the lever 26 to the left thus allowing the valve 9 to seat itself under the pressure of the spring 13. As the movement continues the lower end of the thermostat lever will be brought into engagement with the thumb nut 21 thereby lifting the valve 10 from its seat and allowing the gas back of the diaphragm 5 to flow out through the port 8 into the tubular chamber containing the valve 10. From this tubular chamber the gas escapes either through the port 33 which leads from said chamber into the pipe I or through a port 34 which leads from said chamber to the exterior of the apparatus. In either case the escape of the gas through one of these two ports relieves the pressure on the back of the diaphragm 5, and the pressure on the valve 4 will lift the latter from its seat and allow fuel to flow from the main supply pipe H to the fuel out-let pipe I and thence on to the main burners of the heater where it will be ignited by the flame of the usual pilot light supplied for that purpose. The main gas valve 4 will remain open until the temperature of the water in the heater has been raised to such a point as to cause the thermostat control parts to once more assume the position shown in Fig. 2 in which the valve 10 is closed and the valve 9 is open. It will be observed that the opening and closing movements of this valve are produced respectively by the unbalancing and balancing of the gas pressures on the two sides of the diaphragm member 5 which carries the

valve, and that in consequence of this, these movements are performed with great rapidity immediately after the respective openings of the two valves 10 and 9. With an ordinary gas pressure of about one and one-quarter ounce to the square inch the diameter of diaphragm necessary to support and operate the valve 4 with the required rapidity need not be over four inches; and the space between this diaphragm and the cap 6 necessary to allow the requisite opening of said main valve need not be over one-eighth or three-sixteenths of an inch. Hence the total volume of the chamber between the diaphragm 5 and the cap 6 need not be more than two cubic inches, and this volume of gas can be discharged directly into the room in which the heater is placed without deleterious effects. The control mechanism of storage tank heaters is not, as a rule, operated at very frequent intervals. Even if it operates as many as one hundred times a day that is fifty opening and fifty closing movements (which is many more times than it usually does operate) the total volume of gas discharged into the room in twenty-four hours would aggregate only about one-twentieth of a cubic foot, a quantity altogether too small to be noticed in any way. But it is not necessary in the operation of this device that the port 8 should be opened to the exterior of the apparatus. It can be closed by a cap (shown in dotted lines) thereby compelling all of the gas which flows through the port 8 to pass out through the port 33. It will be noted that at the time the port 8 is opened there is no gas in the pipe I with which the port 33 communicates and gas therefore will escape into this pipe through a port 33 as readily as it will through the port 34. When the valve 4 is opened by the withdrawal of the gas from the back of the diaphragm 5 and the fuel flows through into the pipe I it is prevented from backing up into the port 33 and reestablishing a pressure on the back of the diaphragm 5, both by the form of the port opening 33— which is so located as to act like a reversed ejector orifice—and also by a thin flexible flap valve 35 of leather, chamois skin or similar suitable material.

In the construction shown in Fig. 4 the arrangement of parts is in many respects the same as in the construction of Fig. 2; in fact the two forms of mechanism are practically interchangeable, and differ from each other only in details of the construction and the arrangement of individual parts. In Fig. 4 as in Fig. 2 the casing M contains a main gas valve 4' which is secured to the center of a thin flexible leather diaphragm 5', on the right hand side of this diaphragm, *i. e.*, on the side opposite the gas valve 4', is a shallow chamber, corresponding to the chamber on the left hand

side of the diaphragm 5 of Fig. 2. The gas supply pipe H is led into the upper side of the gas valve casing M, and a port 7' leads from this part of the chamber through a tube 36 into a valve chamber 37. A valve 9' which is normally held against its seat by a spring 13' affords means for opening and closing communication between the valve chamber 37 and a port 38 that leads into the space back of the diaphragm 5'. The stem 15' engages with the recessed central boss of the valve 9', passes through a stuffing box in the cap 39 and terminates opposite the head of an adjustable screw 16' that is threaded into the upper end of the thermostat lever 26'. The stem 15' is provided with a leather faced collar 40, and a spring 41 interposed between this collar and the valve 9' serves to seal the opening around the valve stem—when the valve is closed—even though the stuffing box may be quite loose. The lower portion of the gas valve casing M is provided with a second valve 10' of exactly the same construction and mounted and operated in exactly the same way as the upper valve 9'. The valve chamber 42 is provided with two port openings one of which 33' opens into the gas outlet pipe I, and the other of which 8' leads into the pipe 43 which communicates with the port 44 formed in a perforated division plug 45 in the pilot light tube a (see detail of Fig. 5). The stem 20' of the lower valve 10' terminates opposite the head of an adjustable screw 21' threaded into the lower end of the lever 26'. This lever is of the same general construction as that shown in Figs. 2 and 3 and is actuated by a thermostat member which is also of the same construction as that previously described. The gas valve 4' is provided at its center with an adjustable screw 30' which bears against a light compression spring 31' that aids in holding the gas valve against its seat when the parts 9' and 10' are in position shown in Fig. 4. The operation of this mechanism is the same as that of the construction previously described and will therefore be readily understood without an extended description. The position of parts shown in the figure is that assumed when the temperature of the water in the tank is at or above the point at which the control mechanism is set to cut off the gas to the main burners of the heater. In this position the thermostat member has expanded sufficiently to allow the spring 29' to bring the head of the screw 16' into engagement with the stem 15' of the valve 9' and raise the latter from its seat thus exposing the right hand side of the diaphragm member 5 to the pressure of the gas in the supply pipe H. This pressure on the back of the diaphragm member 5, aided by the pressure of the

4

spring 31' holds the gas valve 4' against its seat and prevents any flow of gas from the pipe H to the pipe I. When the temperature of the water in the tank falls, the 5 thermostat members contract and move the upper end of the thermostat lever 26' to the right thus allowing the valve 9' to seat itself. As the movement of this lever continues, by the continued contraction of the 10 thermostat element, the head of the screw 21' is brought into engagement with the stem 20', and this in turn moves the gas valve 10' away from its seat and allows the gas bac¹ of the diaphragm member 5' to escape either through the port opening 33' or through the port opening 44. Both of these port openings may be left open at the same time or either one may be closed off. If the port opening 33' is left open and the 15 port opening 44 is closed—as by closing the plug valve in the pipe 43—the action will be the same as in the case of the corresponding use of the apparatus of Fig. 2. If the port 33' is closed and the port 44 left open 20 the gas will be siphoned or sucked out through the last named port by the ejector action of the stream of gas which is constantly flowing through the pilot light tube a. This ejector action may be increased by 25 making the perforations 46 in the block 45 smaller in area than the cross-section of the pilot light tube thereby reducing the pressure at the lower surface of the block 45. This reduction in pressure can be still 30 further increased, if desired, by forming the lower end of this block into a mixing chamber through which both air and gas will pass to the pilot light. This latter construction however is not necessary to 35 secure the efficient action of the apparatus, and has not therefore been specifically illustrated. The removal of the gas from the 40 right hand side of the diaphragm 5' allows the gas valve 4' to be opened by the unbalanced pressure of the gas on the right hand side of the diaphragm thus admitting a fuel supply to the gas outlet pipe I and the main heating burners supplied thereby. 45 As the water in the tank is once more heated up the thermostat member will again expand allowing the spring 29' to move the thermostat lever 26' until the head 21' is out of engagement with the stem 20' and the head 16' is in engagement with the 50 stem 15'. This movement of the thermostat lever first allows the valve 10' to close, and next presses the valve 9' open, thereby reestablishing the conditions first described in which both sides of the diaphragm member 5 are exposed to equal gas pressures, and the main gas valve 4' is held 55 closed by the pressure of the spring 31'. The control apparatus shown in Fig. 6 differs somewhat from that shown in any 60 of the preceding figures both in details of con-

struction and of operation. The main frame or the casing M of the apparatus is bolted against a plate 50 which is riveted or otherwise suitably secured to the end or side wall 1² of the tank A. This casing is provided as 70 before with a gas inlet pipe H leading into the top of the casing, and a gas outlet pipe I leading from the bottom thereof to the main burners of the heater. As before the casing is provided with a division wall which separates the inlet and outlet openings and this division wall has a central opening in which the main gas valve 4³ is located. But this gas valve instead of being mounted and supported directly on a diaphragm member as 80 in the preceding construction, is secured to a short stem 51 which projects through the main gas valve port and is provided at the other side thereof with two washers or heads between which the flexible leather dia- 85 phragm is clamped. A port opening 7³ leads from the upper part of the gas valve casing—with which the inlet gas pipe H is in communication—to a vertical tubular chamber 37³, and a second port 38³ leads from the lower end of this chamber into the space back,—i. e., to the right hand of the diaphragm member 5³. The port 38³ is opened and closed by means of a valve 9³, this valve being slidably secured on a stem 52 and held in position thereon by means of a threaded collar 53 and a short compression spring 54. At the lower end of the chamber back of the diaphragm 5³ there is a second 95 port opening 8³ which is provided with two branches, one 34³ leading to the exterior of the apparatus and one 33³ leading to the interior of the gas outlet pipe I. The port 8³ is opened and closed by means of a valve member 10³ which is also slidably secured 100 to the stem 52 by means of a tubular cap 55 and a stem head 56. The stem 52 extends up through the tubular chamber 37³ and an upper part on the stem 52 and serves to keep the stem and its attached parts normally 105 raised to the position shown in the figure. The actuating thermostat is secured in the central boss 58 of the rear head of the gas valve casing, and is of the same construction as that illustrated in Figs. 2 and 4. The terminal knife edge of the inner negative member of this thermostat bears against the short arm of the thermostat lever 26³, and the long arm of said lever is provided with an adjustable screw 59, this screw bearing 110 in turn against the short arm of a second thermostat lever 60. The long arm of the lever 60 engages with the upper end of the stem 52 and is held in engagement therewith by the tension of the spring 57. 115

The operation of the mechanism of Fig. 6 just described is, as already stated, somewhat different from that of the preceding mechanisms. In the case of the last described apparatus the parts are so arranged 120

and adjusted that the main gas valve is closed when there is no pressure on the back or right hand side of the diaphragm 5³, whereas in all of the preceding mechanisms said gas valve is only closed when the corresponding side of the valve supporting the diaphragm is exposed to the gas pressure in the main inlet pipe. Thus, as shown in Fig. 6 the relation of the thermostat elements to the connecting lever mechanism is such that when the temperature of the liquid in the tank is at or above the point at which the fuel supply should be cut off the stem 52 is raised by the spring 57 until the valve 9³ has been closed and the valve 10³ has been opened. Under such circumstances the space back of the diaphragm 5³ will be emptied of gas which passes out either through the port opening 34³, or preferably out through the inclined port opening 33³ into the gas outlet pipe I leading to the main burners. This removal of pressure on the right hand side of the diaphragm leaves the gas valve exposed to the full pressure of the gas on the left hand side of the diaphragm and the valve will therefore be forced at once to its seat thereby cutting off the flow of fuel through the gas valve casing to the main burners of the heater. The gas valve will remain closed—under the pressure of the gas on its left hand side—until the temperature of the water in the tank has fallen to such a point as will cause the successive closing of the valve 10³ and opening of the valve 9³ by the corresponding contraction of the thermostatic member. This is brought about in the following manner: As the temperature of the water falls the outer positive member 23³ of the thermostat will contract thereby moving the terminal knife edge of the inner negative member 24³ to the left. This will move the upper end of the thermostat lever 26³ to the right, and through the action of the second thermostat lever 60 depress the stem 52 against the tension of the spring 57. The downward movement of the stem 52 first allows the valve 10³ to seat itself closing off the opening to the discharge port 8³, the upper valve 9³ remaining seated under the tension of the spring 54. A slight further downward movement of the stem 52 relieves the valve 9³ of the restraining action of the spring 54, and the latter valve will then open allowing gas to pass from the gas inlet pipe H through the ports 7³ and 38³ to the space back of—that is to the right of—the main valve diaphragm member 5³. The pressure of the gas on the face of the main gas valve 4³ immediately opens the latter allowing fuel to flow through the main gas valve port to the gas outlet pipe I and thence on to the main burners of the heater where it is ignited by the flame of the usual pilot light. When the gas valve 4³ is open the both sides of the diaphragm member 5³ are exposed to the same gas pressure, save that the static pressure of the gas on the right hand side is always slightly greater than the kinetic or flow pressure of the gas on the left hand side. The main gas valve will therefore remain open until the expansion of the thermostat member—due to the rise in temperature of the water in the tank—has allowed the parts to once more assume the position shown in Fig. 6, in which the valves 9³ and 10³ have been successively closed and opened. The opening of the latter valve, as already explained, relieves the gas pressure on the back or right hand side of the diaphragm 5³, either by the discharge of the gas into the open air, or by the suctioning out of this gas through the ejector port 33³ past the protecting flap valve 35³. Instead of the gas being discharged from the back of the diaphragm in this manner it may, of course, be discharged or sucked out into the pilot light tube in the same manner already illustrated and described in connection with Fig. 5. In any case the reduction of the pressure on the back of the diaphragm member 5³ by thus removing the gas behind it exposes the other side of this diaphragm to the full unbalanced pressure of the fluid in the main gas valve casing, and this causes the immediate closing of the main gas valve. Thus the turning off and on of the fuel supply to the main burners of the heater under the action of the above described mechanism will be accomplished by practically an instantaneous closure and opening of the main gas valve whenever the temperature of the water in the tank rises above or falls below predetermined points which may be varied as desired by the adjustment of the screw 59 and the adjustment of the collar 53 on the stem 52. This latter adjustment may be conveniently attained by rotating the stem 52 and holding the collar 53 against rotation by means of a lug entering a slot on the adjacent wall of the gas valve casing.

Fig. 7 illustrates a construction of control mechanism which is particularly designed for use on a water heater of the so-called instantaneous type, in which the liquid passes through a coil of copper pipes which are exposed directly to the heat of the main burners. Because of its well known character the structure of the heater upon which the control mechanism is to be used is not illustrated, and it will be understood that the control mechanism is applicable to various types of coil heaters. One of the best known of such types is shown in the patent to Schook, No. 993,723, issued May 30, 1911, and my improved construction is readily applicable to such heater in place of the control mechanism of the said patent. In this

type of heater it is desirable that gas should only be admitted to the main burners while the water is flowing through the heating coils. For this reason the main gas valve 6 used in the construction shown in Fig. 7 is controlled in its movement not only by the thermostatically regulated pneumatic pressure means, but also by the position of a water actuated element placed in the path 10 of the inflowing water to the heater coils. This water actuated element is indicated in the figure by the reference numeral 62. It is located in a cylinder 63 which is provided at its front end with an inlet port in communication with the pipe 64 leading from the cold water main, and is provided at its rear end with a second port which is in communication with the pipe 65 which leads to the cold water inlet 66 entering the top coil of 20 the heating chamber. The piston 62 is perforated at its center to receive a plug 67 which is loosely held in position in the front head of the cylinder 63 by means of a nut 68. A stem 69 is secured to the left hand end of the central perforated boss 62 of piston member 62, passes loosely through the plug 67, and through a stuffing box in the front end of the cylinder head and enters the wall of the gas valve chamber. This 30 stem is provided with a collar and leather washer 70 which serves to seal the opening around the stem 69 and prevent the escape of water through the adjacent stuffing box. The plug 67 is provided with tapered ports 35 71 which are completely closed when the piston member 62 is in the position shown in the figure, but which gradually open as said piston is moved to the left and allow water to flow from the front end of the cylinder through the central perforated boss of the piston to the rear end of the cylinder. The stem 69 extends through the piston 62 and is provided at the extreme left hand end with a spring check valve washer 72 which 40 is held lightly against the adjacent perforated face of the central boss by a weak spring 73. A stiff spring 75 is interposed between the left hand side of the piston member 62 and the rear cap of the cylinder 63, and serves to hold the piston member 45 normally in the position shown in the figure in which, as already stated, the port openings leading from the inlet pipe 64 to the pipe 65 are closed, so that no liquid can flow from the water main into the heater coils. The supply of gas enters the main gas valve casing M through an inlet pipe H, and when the main gas valve is open passes out through the pipe I which leads to the main burners. The main gas valve 76 which controls the flow of fuel is mounted at the center of a thin flexible leather diaphragm 77. A port opening 78 leads from the top portion 50 of the gas valve chamber to a second chamber 79 which contains the thermostati-

cally actuated mechanism by means of which the main gas valve is opened and closed according to the variations in temperature of the flowing water. The thermostat member itself is located in a tube 80, the lower end 70 of which is in communication with the hot water outlet 81 leading from the bottom of the heater coils, and the top end of which is in communication with the pipe 82 through which hot water is led to the house supply system, or to such other point of use as may be desired. This thermostat is of the usual composite construction comprising an outer tube 83 of brass, copper, zinc or other metal having a high coefficient of expansion, and an inner negative element 84 which is made of steel, Invar metal, porcelain, carbon or similar material having a very low coefficient of expansion. The outer positive tubular element is secured at its lower end in 80 the boss which carries the tube 80, is closed at its upper end and at that point is secured or abuts against the adjacent end of the inner negative member 84. The latter terminates at its lower end in a knife edge which 85 bears against a thermostat lever 85, the outer end of which is provided with an adjustable screw 86 engaging with a second thermostat lever 87. The latter lever engages in turn with a stirrup or fork 88 the lower end of 90 which is pressed upwardly against the thermostat lever system by means of a strong compression spring 89. The lower cross-bar of the stirrup 88 is slotted to receive the head of a valve stem 90 carrying the double headed valve 91. The upper head of this valve 91 serves to open and close the port 92 which leads from the chamber 79 to the space back of the main valve diaphragm 77. The lower head of the valve 91 100 serves to open and close a second port 93 leading from the right hand side of the diaphragm 77 to a discharge ejector port 94 which opens into the gas outlet pipe I. A spring 95 is interposed between the head of 105 a downwardly projecting stem secured to the valve 91 and the upper end of the port chamber 94. This spring is of considerably less tension than the spring 89, so that when the valve 91 is acted upon by the former 110 spring alone it will be held in the position shown in the figure thereby closing the port 93; but when said valve is acted upon by both springs it will be raised by the superior tension of the spring 89 thereby closing the 115 port opening 92.

The operation of the control apparatus of Fig. 7 is as follows: When the water is at rest in the heater coils the pressures on both sides of the water actuated member 62 will 125 be the same, this member will be held against the front end of the cylinder 63 by the spring 75. In this position of the piston member the end of the stem 69 which enters the main gas valve chamber, bears against 130

the center of the main gas valve 76 and holds the latter firmly closed against its seat, and prevents its being opened by any action of the thermostatically controlled mechanism. 5 But as soon as water is withdrawn from the heater coils—as by opening a tap in the discharge pipe 82—the pressure in the heating chamber and in the left hand end of the cylinder 63 is reduced, and the piston member 62 is moved to the left thus opening the ports 71 and allowing water to flow from the front end of the cylinder through these ports past the leather check valve 72 and on through the pipe 65 to the heating receptacle to keep up the desired flow through the outlet pipe. This movement of the piston member withdraws the end of the stem 69 from engagement with the main gas valve 76 and leaves the latter free to be actuated in its movements solely by the thermostatically controlled means. If the temperature of the water in the thermostat chamber is less than that desired the thermostat levers 85 and 87 will be depressed to such a position as to keep the lower cross-bar of the stirrup 88 out of engagement with the head of the stem 90, and under these circumstances the valve 91 will be held in its lower position by the spring 95, thus leaving the port 92 open. This will allow gas to pass through the ports 78 and 92 to the right hand side of the diaphragm 77 and the pressure of said gas on this side of the diaphragm will cause the main gas valve 76 to open as soon as the stem 69 has been withdrawn from engagement with its opposite side. Fuel will thereupon flow through the gas valve casing from the gas inlet pipe H to the gas outlet pipe I and pass on to the main burners of the heater where it will be ignited by the usual pilot light provided for that purpose. As the temperature of the water flowing through the ports and the thermostat chamber rises the piston member 83 of said thermostat will expand allowing the thermostat levers 85 and 87 and the stirrup 88 to move upwardly under the tension of the spring 89 until the lower cross-bar of said stirrup engages the head of the valve stem 90 thereby lifting the valve 91 until the port 92 is closed and the port 93 is opened. The gas back *i.e.*—to the right of the diaphragm member 77, will now be discharged or suctioned out through the chamber port 94 into the gas outlet pipe I and the unbalanced pressure of the gas on the opposite side of said diaphragm will close the main gas valve 76 and shut off the supply of fuel to the heating burners. The main gas valve will remain closed until the fall in temperature of the flowing water and the corresponding fall of temperature of the thermostatic elements will cause the parts to once more assume the position shown in the figure whereupon the valve 76

will once more be opened admitting a fresh supply of gas to the heating burners. These opening and closing movements of the main gas valve will continue as the temperature of the flowing water falls below or rises above the point for which the thermostat may be set to act on the control valve 91, this point being varied at will by adjusting the screw 86. But when the flow of water is stopped the pressures on the two sides of the water actuated piston member 62 will at once be equalized, and the said piston member will be returned to its closed position—as shown in Fig. 7—in which, as before stated, the end of the stem 69 is brought into engagement with the main gas valve 76 and holds the latter tightly closed to its seat regardless of the position of the thermostatic control parts. If, for any reason, the water actuated member 62 should stick in its opened position any injury to the heater cannot result, since the main gas valve will under such circumstances remain under the control of the thermostat mechanism and the latter will operate like a straight thermostatic control to shut off the fuel supply to the heating burners whenever the temperature of the water in the heater coils rises above a certain point. To insure the continued maintenance of the thermostat member at the temperature of the water in the heater coils, a circulation valve 97 is provided, which is opened by gravity whenever the flow of water ceases and allows the water to circulate freely between the inlet 100 and outlet openings 66 and 81 and the thermostat tube and cross-connection 98. When the water is flowing this circulation valve 97 is raised by the pressure of the flowing water thus cutting off the port opening to the cross-connection 98 and forcing all of the water to pass through the heating coils. But unless the water actuated member 62 is very tightly wedged in its open position it will be soon forced back to its closed position on the cessation of flow by the action of the leather check valve 72, which, as soon as the flow of water is stopped, automatically closes the perforated end of the central piston boss and thus confines the body of liquid in the heater between the left hand side of the piston 62 and the now closed house service pipe. The expansion of this body of liquid under any further heating exerts a strong pressure on the left hand side of the piston and thus forces it back to the closed position, unless, as already stated, it may be actually blocked open by the wedging of some solid matter in the port opening 71, a contingency that is hardly likely to occur even under the most severe conditions of use.

In Fig. 8 I have illustrated a slight variation of the construction shown in Fig. 7. The apparatus of this latter figure is pre-

cisely the same in all respects as that shown in Fig. 7 save that the water actuated member 100 does not act directly upon the gas valve 76 to hold it closed when no water is flowing but acts upon an auxiliary valve 101 which opens and closes the port 78 through which gas passes from the gas inlet pipe H to the chamber 79.

The operation of this mechanism is the same in all respects as that of the one just described save that when no water is flowing, the closing of the valve 101 by the spring 102 prevents any gas entering the chamber 79 and acting upon the back *i.e.* the right hand side, of the diaphragm 77. This will prevent the gas valve 76 from being opened when no water is flowing no matter what may be the position of the valve 91. When the flow of water is started the water actuated member 100 is moved to the left opening the valve 101 and admitting gas to the chamber 79. The admittance and discharge of gas to and from the back of the main gas valve diaphragm 77 is then controlled by the movement of the valve 91 under the action of the thermostatic control mechanism in exactly the same way as in the apparatus shown in Fig. 7; and as long as water continues to flow the opening and closing of the main gas valve 76 will be controlled entirely by the thermostatically actuated parts, the fuel being shut off when the temperature of the flowing water rises to a predetermined point and turned on again when the temperature of said water falls below that point. When the flow of water stops the member 100 will be returned to its seat thereby closing the port opening 78 and preventing any further access of gas to the back of the main gas valve diaphragm 77. After the very next movement of the thermostat which discharges the gas in that chamber the actuating pressure means which operates the main gas valve is eliminated and said gas valve will therefore remain permanently closed under the pressure of the gas on the main gas valve side of the diaphragm until the port 78 has once more been opened by reestablishing a flow of water through the heater coils and a new supply of gas admitted to the chamber 79.

In Fig. 9 I show another embodiment of my improved control mechanism as designed for use on the so-called instantaneous type of water heater. In this construction I place the chamber 63⁴ which contains the water actuated member 62⁴, above the thermostat chamber 80⁴; and lead the stem 69⁴ of said water actuated member down through a stuffing box 103 and along the side of the thermostat chamber 80⁴ through another stuffing box on the top of the main gas valve casing M which is secured to and forms a part of the lower end

of the thermostat chamber 80⁴. Cold water is led into the lower end of the piston chamber 63⁴ through a pipe 64⁴. The piston member is somewhat similar in construction to that shown in Fig. 7 being provided with a downwardly projecting inwardly coned annular valve seat, which fits loosely around an outwardly coned upwardly projecting boss 104 on the lower head of the cylinder, the space between these two adjacent members forming—when the piston is raised—a port or passage way through which the water can pass from the inlet pipe 64⁴ to the cold water inlet 66⁴ to the top coil of the heater. The central part of the piston member 62⁴ is provided with small ports 105 which lead from the opening communicating with the inlet 66⁴ to the upper end of the cylinder 63⁴, and a flat puppet valve 106 is hung on a stem 107 loosely mounted in the top cap of the cylinder, in such manner as to close these ports 105 as soon as the piston member begins its upward movement. This valve 106 is held down by a spring interposed between it and the top cap of the cylinder, and a second spring concentric with this first spring is interposed between the top of the piston 62⁴ and this same cap for the purpose of holding said piston normally in the position shown in the figure. The water after entering the inlet 66⁴ and passing through the coils of the heating receptacle, emerges from the hot water outlet 81⁴, enters the lower end of the thermostat chamber 80⁴, passes up through the latter, and finally enters the pipe 82⁴ which communicates with the house supply system. At the upper end of the cylinder 63⁴ there is a port 108 which opens into the pipe 82⁴—when the piston member is in its lowest position and the ports 105 are open—and allows the water to circulate through the thermostat chamber between the inlet 66⁴ and the outlet 81⁴ of the heater coils. Located in the thermostat chamber 80⁴ is the controlling thermostat member, which is of the same general construction as that shown in Fig. 7, save that in this case the inner negative element 84⁴ is provided with pivot points or knife edges at both ends, and is preferably of larger diameter at the center than at the ends so as to resist more effectively the compression strain exerted on this part when the outer positive element 83⁴ of the thermostat contracts. The lower knife edge or pivot point of the inner thermostat element 84⁴ engages with the short arm of a thermostat lever 109. This thermostat lever differs from any previously described in that the axis of the short arm is not normally disposed to the line of engagement of the thermostat member but is arranged at large angle thereto, the purpose of this arrangement being to secure a large multiplication of the move-

ments of the thermostat element without the necessity of using a long thermostat lever or without the necessity of using a compound thermostat lever system such as is commonly employed, and such for example, as is shown in Fig. 7. The horizontal arm of the thermostat lever 109 is provided at its outer end with an adjustable screw 110, and the axis of this arm is normally disposed to the line of movement of the valve stem 90⁴ with which the screw 110 engages. This valve stem passes out through a stuffing box and is secured to a valve 91⁴ which serves by its upward and downward movements to open and close the two ports 92⁴ and 93⁴. The first of these ports communicates with a passage way 78⁴ which leads to the chamber through which gas is admitted from the main inlet pipe H to the main gas valve casing, and the second of said ports communicates with the passage way 94⁴ which leads to the ejector discharge orifice opening into the gas outlet pipe I. The valve head 91⁴ is normally held in its upper position, so as to close the port 92⁴ and open the port 93⁴ by a compression spring 111. The main gas valve 76⁴ is mounted in a horizontal position at the center of a thin flexible leather diaphragm 77⁴, and when no water is flowing through the heater this valve is held down against its seat by the engagement of the lower end of the stem 69⁴ with the upper side of the valve head. In this construction I also mount the usual cut-off plug valve, which is provided for entirely shutting off the supply of gas, directly in the chamber with which the gas supply pipe H communicates; and I provide a cored passage way 112 leading around the outside of this main cut-off valve to a tube 113 which leads to the pilot light.

The detail character of the operation of this mechanism is slightly different from that of the mechanism of Fig. 7 and is as follows: When no water is flowing through the heater the piston member 62⁴ is in its lowest or closed position as shown in the figure, and all communication is cut off between the pipe 64⁴ and the cold water inlet 66⁴, save for such small flow as is usually provided for to take care of the discharge from leaky faucets. As soon as any large flow of water is set up, as by opening the faucet in one of the house supply pipes, water is rapidly withdrawn from the upper end of the cylinder 63⁴ through the port 108, and the superior pressure of the water on the lower side of the piston member then raises the latter thereby closing the ports 105 and opening the main ports leading from the lower end of the cylinder to the cold water inlet 66⁴. This lifting of the piston member withdraws the end of the stem 69⁴ from engagement with the back of

the main gas valve, and leaves the latter free to be moved by the thermostatically regulated gas pressures on the main valve diaphragm 77⁴. If the temperature of the flowing water is less than that for which the thermostat control mechanism is set to act, the thermostat lever 109 is lifted to such position that the screw 110 is out of engagement with the stem 90⁴, and the valve 91⁴ is therefore raised by the spring 111 so as to leave the port 93⁴ open and relieve the upper side of the main gas valve diaphragm 77⁴ from any pressure save that of the atmosphere. The lower side of the diaphragm 77⁴ is however constantly exposed to the pressure of the gas entering the gas valve chamber from the supply pipe H, and this pressure raises the main gas valve 76⁴ from its seat as soon as the restraining pressure of the stem 69⁴ on the back of this valve has been removed. This allows the supply of fuel to pass from the supply pipe H through the main cut-off valve and through the chamber of the gas valve casing M and flow out through the gas outlet pipe I to the main burners of the heater where it is ignited by the flame of the pilot light supplied through the pipe 113. As the temperature of the flowing water rises the thermostat member expands lifting the negative thermostat member 84⁴ and allowing the thermostat lever 109 to be depressed by its spring 114 until the screw 110 has made engagement with the end of the stem 90⁴ and moved the valve 91⁴ down until the lower port 93⁴ has been closed, the port 92⁴ being simultaneously opened. Gas will now flow through the passage way 78⁴ and port 92⁴ on into the shallow chamber back, i. e., on the upper side, of the main gas valve diaphragm 77⁴, and the gas pressures on the two sides of this diaphragm now being balanced the main gas valve 76⁴ will be closed by gravity thus shutting off the flow of fuel to the gas outlet pipe I and to the main heating burners supplied thereby. The temperature of the flowing water will thus immediately begin to fall and this will cause the thermostat to contract thereby lifting the thermostat lever 109 and withdrawing the screw 110 from engagement with the valve stem 90⁴. This in turn will allow the valve 91⁴ to be lifted by its own spring 111 to the first described position in which the port 92⁴ is closed and the port 93⁴ is opened. The opening of this latter port allows the gas back of the diaphragm 77⁴ to flow out through the passage way 94⁴ and the ejector orifice at the end thereof into the now empty gas outlet pipe I. As soon as the pressure of the gas on the top of the diaphragm has thus been relieved the unbalanced pressure of the gas on the lower side thereof will once more lift the main gas valve 76⁴ from its seat and admit a fresh supply of fuel to the

burners. As long as water continues to flow through the heater, the stem 69⁴ is kept lifted out of engagement with the back of the main gas valve, and the latter will continue its opening and closing movements under the control of the above described thermostatic mechanism, the point of cut-off being varied at will by the adjustment of the screw 110. But as soon as the flow of water is stopped the water actuated member 62⁴ will be returned to its lowest position both by the action of gravity, and by the action of the springs in the cylinder 63⁴, and the stem 69⁴ will once more be brought into engagement with the top of the main gas valve 76⁴ holding this valve closed, no matter what may be the position of the thermostatically controlled valve 91⁴. When the piston 62⁴ is in its lowest position the ports 105 are opened, as already explained, thus affording an open passage for the circulation of water through the thermostat chamber between the inlet and outlet openings to the top and bottom of the heater coils.

Instead of discharging the gas above the main gas valve diaphragm through the ejector orifice at the end of the passage way 94⁴ into the main gas outlet pipe I, I may of course discharge it into the pilot light tube 113 through an ejector port—indicated by dotted lines only—similar to that illustrated in Fig. 5.

In Figs. 10 and 11 I have illustrated, somewhat diagrammatically, another construction of thermostat member and thermostat lever which may be used—with such slight modifications as are readily apparent to any one skilled in the art—in conjunction with any of the previously described mechanisms. The particular advantage of the thermostat mechanism shown in these figures is that it occupies a very small amount of space, and is also of very simple and inexpensive construction. It consists of a central bar 115 of trapezoidal cross-section (see Fig. 11) supported at its center in any suitable manner on the wall of the thermostat chamber or box, and terminating at each end in a knife edge which forms a bearing for a segment of a small grooved coned pulley. This bar is made of nickel steel, invar metal, or some other material having a very low or practically zero coefficient of thermal expansion. In the upper one of these pulleys 116 the radii of the successive pulley steps are in the ratio of the even number, 2, 4, 6, 8, etc.; in the lower pulley 117 these radii are in the ratio of the odd numbers 1, 3, 5, 7, 9, etc. One end 118 of a wire, which is preferably made of hard drawn copper, silver, brass, German silver or phosphor bronze, is secured to the upper end of the bar 115, and is passed around the successive steps of the lower and upper coned pulleys 117 and 116 as shown

in the figure, and is secured at its outer free end 119 to the short arm of a thermostat lever 120. It will be readily seen that when this wire expands or contracts with reference to the central bar 115 the movement of that part of the wire which engages with the successive steps of the pulley elements is exactly the same as the circumferential movement of those steps themselves so that, with a uniform angular movement of all of these pulley elements as a whole there is no slipping of successive parts of the wire on the steps with which these parts engage. The thermostat lever is of the same general construction as that illustrated in Fig. 9, that is to say the axis of the short arm is out of alignment with the long arm of the lever; and the vertical plane of the point of attachment 119 between the wire and short arm of the lever may be placed as close as desired to the vertical plane of the fulcrum *m* thus giving the desired multiplication of movement at the screw *p* without using a multiplicity of levers and without using a lever having an undue over all length. It is further readily seen that this expansion and contraction movement of the point 119 is the same as that which would be obtained for the same change in temperature with a straight wire whose total length was equal to the sum of the lengths of all the strands or sections of wire running between the two opposing coned pulley members. If the length of each of these strands, *i.e.*, the length of the bar 115 between its terminal knife edges, is made only three inches, and the total number of strands is fifteen—as shown in the figure—the total expansion and contraction effect is the same as would be secured with a straight wire forty-five inches long. The difference between the coefficients of expansion of hard drawn wires such as I have already referred to and nickel steel bars is about .00001. Hence the linear movement of the end of the long arm of the thermostat lever 120 and of the part 121 moved thereby would be about one-eighthieth of an inch for every change of temperature of 1 degree C. if the parts were of the dimensions above assumed, and the length of the long and short arms of the lever 120 were in the ratio of thirty to one. This would mean a movement of the part 121 of over one-eighth of an inch for every 10 degrees change in temperature—a movement that is ample and even excessive for the operation of such parts as are to be moved in mechanisms of the class under consideration. The actual dimensions of the parts will of course vary according to the force which it is desired to exert upon the part 121. In water heater constructions such as this application describes the force required to move the thermostatically controlled parts is very

small, and a No. 20 to No. 24 gage wire is 5 amply large to exert the required force on the thermostat lever without permanent stretching or distortion. For wire of this small diameter the coned pulley elements may be correspondingly small, and the 10 whole thermostatic mechanism—lever and all—inclosed in a shallow rectangular box about five inches long, one and one-half inches wide and one-quarter of an inch 15 deep. The side of the box may be left open and the mechanism immersed directly in the stream of hot water or the box may be closed—or if desired may be partially filled 20 with oil—the stem 121 being led out through a suitable stuffing box.

It will now be readily apparent to those reading the preceding description of various mechanisms which embody my improvements, that various modifications may be 25 made in said mechanisms without departing from my invention, and that the said mechanisms and modifications thereof may be applied to various types and classes of water 30 heaters with only such detail changes as will be readily understood and appreciated by those skilled in the art.

Having thus described my invention and 35 illustrated its use, what I claim as new and 40 desire to secure by Letters Patent, is the following:

1. In combination in a water heater system, a burner, a conduit for supplying gas to the burner, a valve in the conduit, means 45 operated by the pressure of the gas in the conduit for opening and closing the said valve, thermostatic means operated by the water in the system for controlling said last mentioned means, and means controlled by 50 the water pressure whereby the said valve is held closed until the outlet from the heater is opened.

2. In combination in a water heater system, a burner, a conduit for supplying gas to the burner, a valve in the conduit, a thermostat operated by the water of the system, 55 actuating means operated by the pressure of the gas in the conduit for opening and closing the said valve, means interposed between the actuating means and the thermostat and controlled by the thermostat for governing the application of the pressure of gas in the conduit to the said actuating means, and means controlled by the water pressure whereby the said valve is held closed until the outlet from the heater is opened.

3. In combination in a water heater system, a burner, a conduit for supplying gas to the burner, a valve in the conduit, a thermostat operated by the water of the system, a movable member operated by the pressure of the gas in the conduit for opening and closing the said valve, pilot valve means controlled by the thermostat whereby the gas

upon the said member is controlled, and means controlled by the water pressure whereby the said valve is held closed until the outlet from the heater is opened.

4. In combination in a water heater system, a burner, a conduit for supplying gas to the burner, a valve in the conduit, a thermostat operated by the water of the system, a movable member operated by the pressure of the gas in the conduit for opening and closing the said valve, pilot valve means controlled by the thermostat whereby the pressure of the gas on one side of the member is controlled, and means controlled by the water pressure whereby the said valve is held closed until the outlet from the heater is opened.

5. In combination in a water heater system, a burner, a conduit for supplying gas to the burner, a valve in the conduit, a thermostat operated by the water of the system, a movable member operated by the pressure of the gas in the conduit for opening and closing the said valve, pilot valve means controlled by the thermostat whereby the gas pressure is admitted to and exhausted from one side of the said member to secure the movement thereof, the gas pressure on the other side of the member being substantially uniform, and means controlled by the water pressure whereby the said valve is held closed until the outlet from the heater is opened.

6. In combination in a water heater system, a burner, a conduit for supplying gas to the burner, a valve in the conduit, a thermostat operated by the water of the system, a movable member operated by the pressure of the gas in the conduit for opening and closing the said valve, pilot valve means controlled by the thermostat whereby the gas pressure is admitted to one side of the said member to cause the closing of the valve when the temperature of the water rises above a given point, and whereby the gas pressure is cut off from such side of the member, and the gas then exhausted from such side of the member when the temperature of the water drops below a given point, and means controlled by the water pressure whereby the said valve is held closed until the outlet from the heater is opened.

7. In combination in a water heater system, a burner, a conduit for supplying gas to the burner, a main valve in the conduit, a thermostat operated by the water in the system, a movable member operated by the pressure of the gas in the conduit for opening and closing said valve, a pilot valve for admitting gas pressure behind the said member to cause its actuation and the actuation of the said main valve, an exhaust passage leading from behind the main valve to the outlet side of such valve, an exhaust valve for controlling the flow of gas through said

passage; and a check valve for preventing a back flow through said passage, the pilot and exhaust valves both being actuated from the thermostat, and the pilot valve being opened when the exhaust valve is closed and vice versa.

In testimony whereof I have hereunto

signed my name in the presence of the two subscribed witnesses.

FRANK L. O. WADSWORTH.
